CLAIM

The ornamental design for shelf dispensing unit, as shown and described.

DESCRIPTION

FIG. 1 is a perspective view of the design; FIG. 2 is a front view of the design of FIG. 1; FIG. 3 is a back view of the design of FIG. 1; FIG. 4 is a first side view of the design of FIG. 1; FIG. 5 is a second side view of the design of FIG. 1; and, FIG. 6 is a top view of the design of FIG. 1. In the drawings, the broken lines depict environmental subject matter only and form no part of the claimed design.

1 Claim, 6 Drawing Sheets(56)
